REMOVABLE WEARING SURFACE FOR
RUBBER HEELS

Frederick A. W. Kelley, Pawtucket, R. I.

Application January 23, 1940, Serial No. 315,178

3 Claims. (Cl. 36—36)

My present invention relates to rubber heels, and more particularly to removable wearing surfaces comprising a portion of said heels.

Heretofore, it has been the practice with the users of rubber heels to have an entire new set of heels replaced on his or her shoes from time to time to take care of the wear which normally occurs in footwear of this type.

It is generally recognized that such wear, in the great majority of instances, is located on the outer rear edge of the heel. In almost every instance the inner central portion and the forward, or throat portion of the heel, is practically perfect.

Having the above defects, in rubber heels in mind, I have designed a new rubber heel having a renewable rear wearing section which may be replaced, at the will of the user.

I am fully aware that the above shortcomings of the conventional rubber heels has already been recognized, as set forth in the prior art, wherein it has been attempted to correct the fault by means of the use of vulcanized rubber having a harder or more solid characteristic than the rest of the heel.

In my present invention, I wish to especially point out the fact that, in my improved heel, the entire wearing surface may be of the same resiliency throughout, thereby eliminating any and all hard or non-uniform areas, which tend to detract from the desired cushioning effect which the rubber heel user is entitled to receive.

Therefore, the principal object of my invention, is an improved rubber heel;

Another object is an improved rubber heel constructed from two parts one of which is renewable;

Still another object is an improved rubber heel having a renewable wearing portion which is easily replaced by the user without the aid of a shoemaker or special tools or equipment, and

Other objects and novel features comprising the construction and operation of my invention will appear as the description of the same progresses.

In the drawing illustrating the preferred embodiment of my invention:

Fig. 1 is a bottom plan view of the assembled heel;

Fig. 2 is also a plan view of the bottom of the heel but showing the removable portion partially withdrawn from the fixed portion;

Fig. 3 is a side elevation of the assembled heel, as disclosed in Fig. 1;

Fig. 4 is a cross-section of the heel taken on the line 4—4 of Fig. 3;

Fig. 5 is a cross-section taken on the line 5—5 of Fig. 1;

5 Fig. 6 is a top plan view of the removable heel member;

Fig. 7 is a cross-section taken on the line 7—7 of Fig. 1, and

Fig. 8 is a rear elevation of the heel with the removable heel member withdrawn from the fixed heel portion.

Referring more in detail to the drawing 10 indicates the fixed portion of a rubber heel and 11 indicates the removable portion.

15 In my improved heel the fixed portion 10 is composed of rubber having a substantially rigid plate 12 imbedded therein. The rear portion of the fixed rubber heel 10 is provided with a step-cut area extending from the bottom surface of the heel up to the surface of the plate 12. In the drawing, I have indicated by a dot-and-dash line 13 the vertical side of the step-cut surface which is placed at an angle with respect to the major axis of the heel 10.

20 25 The material comprising the plate 12 may be metal, fibre, or other sheet material found suitable for the purpose.

In Fig. 4, the entire lower surface of the plate 12 is exposed. The surface to the right side of

30 35 the line 13 is entirely covered with rubber except in the central portion between the slideways 14. This area is cored out to leave a thin slot 15 within which fits the tongue member 16 on the removable member 11. The slideways 14 are punched out and folded up from the cut-out openings 17 shown in Fig. 4, through which rubber is flowed in the vulcanizing of the heel. It

40 45 will be noted that the plate 12 is preferably made slightly smaller in outline than the outline of the heel such that the edges of the plate 12 are hidden. At various points, as 18, round openings are provided in the plate 12 through which rubber is vulcanized, as in the case of the openings 17.

On that portion of the plate 12 to the left of the line 13, I have provided a plurality of semi-circular depressed members 19. These semi-circular members are bent down and are imbedded in the rubber of the extension portion, to the left of the line 13, of the fixed heel portion 10. The same semi-circular members are provided in the area between the slideways 14, see Fig. 4.

The fixed heel portion 10 is secured to a shoe by the conventional nails 20 in the usual manner.

55 At the rear central portion of the plate 12, I

have provided a raised strap portion 21 which is formed up from the plate 12 under which slides the tongue member 22 formed on the plate 23 which is imbedded in the removable heel portion 11 of which the tongue 16 is a continuation. This plate 23 is provided with depressed semi-circular members 19 which are imbedded in the rubber of the removable member 11. Similar to the plate 12 in the heel portion 10, the plate 23 is of a less radius than the outline of the rubber portion so that it is hidden when the member 11 is in place with the member 10.

In the tongue portion 16, I have provided an opening 24. When the removable member 11 is assembled with the fixed heel portion 10, the opening 24 is in alignment with the screw 25 which provides a lock maintaining the two heel members in their assembled position as shown in Figs. 1 and 3.

Preferably, the angle of the line 13 is such that the long end of the member 11 is on the outside of the shoe when in use, the illustrations in the drawing showing a right-hand heel. The left-hand heel is identical excepting that the angle of the line 13 is reversed.

In operation, the removable member 11 is assembled with the fixed member 10 by sliding the tongue 16 of the removable member 11 into the slot 15 of the fixed member 10 and at the same time engaging the tongue member 23 under the strap 21 at the rear of the plate 12. When in place, the screw 25 is inserted through the fixed heel portion 10 and the opening 24 in the tongue 16, as shown in Fig. 5.

It is to be understood that I may use any type of material in the plates 12 and 23 found suitable and that I may use any other form of clincher members in place of the semi-circular

members 19. The openings 18 may also be of any size or shape, or if a material is used which will properly bond with the vulcanized rubber, I may eliminate such clincher members and openings.

5 It is also to be understood that I may vary the shape and proportions within wide limits without departing from the spirit of the invention.

Having thus described my invention what I

10 claim as new is:

1. An improved rubber heel comprising in combination, a fixed front portion having a rigid member imbedded therein with a slideway formed therefrom, a removable back portion having a rigid tongue member engaging in said slideway, and means for locking said portions together.

2. An improved rubber heel comprising in combination, a fixed front portion and attached base, said members having an imbedded plate member therein, a slideway formed from said plate, a removable back portion having an imbedded plate therein and extending tongue portion, said tongue portion engaging in said slideway, and means for locking said back portion to said front and base portion.

3. An improved rubber heel comprising in combination, a fixed front and base member, a plate imbedded in said front and base members, a slideway formed from said plate member and a slot located in said front portion, a removable back portion having a plate imbedded therein and having an extending tongue portion engaging in said front portion slot and slide way, an orifice extending through said front and base portion and through said tongue portion, a screw located through said orifice for the purpose of locking said members together.

FREDERICK A. W. KELLEY.
